TIRE

George W. MacWherter, Wadsworth, Ohio, assignor to
The B. F. Goodrich Company, New York, N.Y., a
corporation of New York

Filed Mar. 15, 1966, Ser. No. 1,469

Term of patent 14 years

(Cl. D90—20)

Fig. 1

Fig. 2

FIG. 1 is a perspective view of a tire showing my new design, it being understood that the tread and sidewall configurations shown in full lines are repeated throughout the circumference of the tire, the opposite side of the tire being identical to that illustrated; and

FIG. 2 is a transverse sectional view through the tire taken substantially on the plane indicated by the line 2-2 of FIG. 1.

I claim:

The ornamental design for a tire, substantially as shown and described.
